LIQUID FILLING APPARATUS

John Torigian, New York, N. Y.

Application May 22, 1941, Serial No. 394,672

2 Claims. (Cl. 222—158)

This invention relates generally to packing devices and more particularly to liquid filling apparatus especially adapted for the elimination of difficulties encountered in the operation of filling ampoules, vials and other small containers.

Among the objects of the present invention lies the provision of apparatus of the class described, which is especially suitable for use in the pharmaceutical and cosmetic industries wherein relatively small ampoules, vials and similar diminutive containers must be accurately and quickly filled and wherein the exact amount of material which will be deposited in the container may be positively predetermined and conveniently changed.

Another object herein lies in the provision of liquid filling apparatus which is of such construction that the same may be maintained in a sanitary sterile condition, the apparatus being capable of subjection to the requisite heat and pressure without deleterious effects.

Filling machines constructed in accordance with the present invention are suitable for handling many types of liquids, such as injectable solutions, serums, vaccines, eye drops, nasal drops or inhalants, vial perfumes, tincture of iodine, mercurochrome solution and many other liquids possessing a medium viscosity.

Another object herein lies in the provision of a fluid filling machine which is gravity operated under manual or pedal control permitting a complete elimination of electric wiring, motors and artificial vacuum or pressure.

In accordance with the present construction devices may be fabricated which are light in weight and portable and require only a few square feet of table space without any operation. The construction also permits of the use of materials which are not effected by the fluids handled by the machine.

Another object herein lies in the provision of a device of the class described in which the apparatus is replaceable and interchangeable and is readily dismantled and reassembled in a short time for the purpose of cleaning, adjusting or repairing the apparatus.

In accordance with the present construction by the use of a relatively small number of measuring chambers, a comparatively large range of size containers may be filled.

By reason of the novel construction of the present device, a considerable number of transparent parts are utilized so that the transfer of the liquid is visible at many points during the entire operation.

In accordance with the present invention, adjustment of the device requires only a few minutes without loss of material at the beginning, during or near the end of the filling operation.

The present device may be utilized in conjunc-

tion with any suitable reservoir for the liquid and the operator thereof need have no special skill or training.

By reason of the improved construction of the present device, the shut off of flow is accomplished in a positive manner so that drops are not deposited on the inside of necks of ampoules, thereby interfering with proper sealing or producing carbonization.

These objects and other incidental ends and advantages will more fully appear in the progress of this disclosure and be pointed out in the appended claims.

In the drawings, forming a material part hereof, similar reference characters designating corresponding parts throughout the several views in which

Figure 1 is a front elevational view of the device mounted upon a supporting surface.

Figure 2 is an enlarged fragmentary front elevational view partly in section showing in detail the valving mechanism. In this figure the valve is in the measuring chamber filling position.

Figure 3 is a fragmentary enlarged vertical sectional view of the measuring chamber as might be seen from the plane 3 on Figure 4.

Figure 4 is a side elevational view of Figure 1 as seen from the right side thereof.

Figure 5 is a view taken similarly to Figure 2 showing the valving mechanism in the ampoule filling position thereof.

In accordance with the invention, the liquid filling apparatus generally indicated by numerals 10 comprises generally a reservoir 11; a frame 12; a reservoir conduit 13; a measuring chamber 14; a measuring chamber conduit 15; a valving mechanism 16; a measuring chamber control 17; a valving mechanism control 18; and a valving mechanism control regulator 19.

The frame 12 includes a frame base 22, a lower pole portion 23, and an upper pole portion 24. The pole portions 23 and 24 are detachably interengageable at 26 in any well known manner as, for example, by means of a male threaded connection. The purpose of this detachable interengagement of the upper and lower pole portions is to provide greater portability so that the device may be simply dismantled for transportation. The apparatus 10 may be placed upon any suitable surface and as illustrated in the drawings, the numeral 21 designates a table top or other supporting surface to which the foot 20 of the frame base 22 is suitably secured by means of screws 51. The lower end 52 of the lower pole portion 23 is threadedly engageable in the enlargement 54 of the frame base 22 and is provided with an orifice 53. Thus,

the frame base 22 supports the pole portions

23 and 24 as a unit in fixed relationship to the supporting surface 21 perpendicularly thereto.

The reservoir 11 may be of any desired construction but is preferably a container made of glass provided with a filling port 55, a closure for said port 56, a neck 57, an outlet 58 and an outlet valve 59. The reservoir 11 is adjustably maintained in position with relation to the rest of the device by means of the reservoir support clamp 60. The clamp 60 is an articulatable unit including the pole engaging member 61, the link 62 and the reservoir neck engaging member 63. By manipulation of the wing nuts 64, 65 and 66 a universal type of connection is provided between the reservoir 11 and the pole 24 so that the reservoir may be adjusted to any desired position.

The reservoir 11, while previously described as being preferably constructed of glass, may, of course, be composed of any suitable material. Glass is a desirable material because being transparent the amount of liquid in the reservoir may be readily determined and the condition of the liquid in the reservoir may also be examined. Furthermore, being made of glass, the reservoir may be sterilized. The valve 59 is preferably of a comb type having a glass valving member (not shown) which has a ground fit in its seat.

The measuring chamber 14 is preferably composed of glass having a large central bore 67, a small bore 68, a neck 69 and an enlarged portion 70. The measuring chamber 14 is provided with a piston 71, the external diameter of which is substantially equal to or slightly less than the internal diameter of the bore 67. The piston 71 is preferably composed of glass and is adapted for vertical reciprocation within the bore 67. The movement of the piston 71 is limited at the lower extent of its travel by engaging the shoulder 72 disposed between the bores 67 and 68; and said piston is limited in the upper extent of its travel by abutting the lower end of the measuring chamber control 17. The neck 69 by virtue of the bore 68 therein forms an inlet or outlet to the bore 67 of the measuring chamber 14. The measuring chamber 14 is supported in position with relation to the pole portions 23 and 24 by means of a measuring chamber supporting clamp 73. The clamp 73 includes a pole engaging portion 74 which is actuated by the wing nut 75 and at the other end thereof is provided with an enlargement 76 provided with a vertically disposed threaded orifice within which the control 17 is threadedly engaged. Depending from the clamp 73 and adjustably positioned with relation thereto is a link 77. The link 77 is rotatable about a vertical axis and may be secured in any adjusted position thereof by means of the wing nut 78. Laterally extending from the link 77 are a pair of measuring chamber engaging clamps 79 and 80. These clamps are adapted to detachably engage the enlarged portion 70 of the measuring chamber 14 when the screws 81 and 82 are manipulated. The inner ends of the clamps 79 and 80 are, of course, secured to the link 77.

It may thus be seen that the measuring chamber 14, the control 17 and the clamp 73 together with the parts associated therewith are movable as a unit vertically along the pole portions 23 and 24.

Turning now to the valving mechanism the same comprises a main cylinder 84 and a piston valve element 85. The cylinder 84 includes a

measuring chamber connector 90, a reservoir inlet 91 and a valve outlet 92. The cylinder 84 may be formed either of metal or a character not affected by the fluids with which the machine is to be used or may be composed of glass. The cylinder 84 is provided at one end thereof with a valve washer 93 which together with the closure member 90 prevents any leakage of the fluid out of that end of the cylinder 84. The measuring chamber connector 90 may be in the form of a tubular extension extending upwardly from the cylinder 84 and integral therewith. The connector 90 is coupled to the neck 69 by means of a resilient tube coupler 95. The reservoir inlet 91 may be in the form of a curved tubular extension extending upwardly from the lower portion of the cylinder 84 and integral therewith. The reservoir inlet 91 is connected to the reservoir outlet 58 by means of the reservoir conduit 13 and the resilient tube couplers 96 and 97. The valve outlet 92 may be in the form of a tubular extension extending downwardly from the lower portion of the cylinder 84 and integral therewith. The valve outlet 92 is coupled to the ampoule injector 98 by means of a resilient tube coupler 99. The injector 98 may be in the form of a hypodermic type needle or other tube of small bore and diameter having an enlarged upper end 100.

The cylinder 84 is maintained in position by means of the clamps 101 and 102. The clamps 101 and 102 are actuated by means of screws 103. The lower ends of the screws 103 engage the supports 104 which extend forwardly and horizontally from the upper portion of the frame base 22. The supports 104 are maintained securely in position by the fins 105 which are integral therewith and the base 22. The inner forward portions of the clamps 101 and 102 present concave surfaces toward the cylinder 84, and this is also true of the upper forward surfaces of the supports 104. The cylinder 84, as previously stated, has disposed within the horizontally disposed bore thereof the piston 85. The piston 85 may be composed either of metal which is not affected by the material being dispensed by the device, or of glass and is adapted for horizontal reciprocation within the cylinder 84. The piston 85 is provided with a pair of oppositely arranged angularly disposed channels, a measuring chamber filling channel 107 and a measuring chamber emptying channel 108. The left end of the piston 85 is provided with a hook member 109 and with a fixed flange 110 in the form of a washer secured to the piston. Disposed between the left end of the cylinder 84 and the flange 110 is a spiral expansive spring 111 and a resilient faced washer 112. The action of the spring 111 is to maintain the piston 85 in the position shown in Figure 2, that is, the position in which the channel 107 forms a passage from the reservoir inlet 91 to the measuring chamber connector 90.

The piston 85 is moved to the ampoule filling position thereof as indicated in Figure 5 by pedal pressure upon the valving mechanism control 18. The pressure plate 114 is vertically adjustable along the rod 115. Thus, as seen in Figure 1, pressure to the left upon the plate 114 by means of the bell crank structure 87 will move the link 86 to the right thus pushing the piston 85 to the position shown in Figure 5. The link 86 is provided with a pin 120 which detachably engages the hook member 109 so that by merely lifting the link 86 about the pivot 121, the valving mechanism control 18 becomes pivotally detached from the

piston so that the same may be pulled out of the cylinder. The movement of the piston to the right is controlled by the upper arm of the bell crank 87 striking against the valve regular 88 which is in the form of a screw having a lock nut therefor. The bell crank journal 89 is provided with a bracket 122 for suitably securing the same to the upper surface of the table or supporting surface 21. The two positions of the piston are thus controlled in the measuring chamber filling position by the regulator 88 and by the measuring chamber emptying position by the spring 111 and the action of gravity upon the rod 115 and the pressure plate 114. The angular relation of the rod 115 and the arm 123 (the two principal components of the bell crank 87) may be either fixed and non-adjustable, or may be of two piece construction so that said angular relationship may be adjusted.

Operation

One mode of operation of the device is substantially as follows:

The reservoir 11 with the valve 59 in the closed position thereof is filled with the desired material to be dispensed and is secured in position by means of the reservoir support clamp 60. The outlet 58 is connected to the reservoir inlet port of the valving mechanism 16 by means of the couplers 96 and 97 and the tube or conduit 13. The measuring chamber is connected to the measuring chamber connector 90 by means of the coupler 95 and the ampoule injector 98 is connected to the valve outlet by means of the coupler 99. The valve mechanism is adjusted so that the piston takes the position shown in Figure 2. This adjustment may be accomplished by an adjustment of the bell crank or by an adjustment in the expander force of the spring 111. The valve or pet-cock 59 is moved to the open position thereof and the fluid in the reservoir will pass downwardly through the coupler 97, the conduit 13, the coupler 96, the inlet 91, the channel 107, the measuring chamber connector 90, the coupler 95, the neck 69 and will compress air below the lower surface of the piston 71. The control 17 is rotated to a very much elevated position so that the piston 71 rises to a point whereby the air imprisoned therebeneath may escape to the atmosphere as soon as the liquid starts to flow into the upper entrance of the bore 67. The control 17 is lowered to any desired position depending upon the amount of liquid it is desired that the device shall dispense with one reciprocation of the piston 85. This adjustment of the regulator may be accomplished either by filling test containers of known measure or by calibrating the measuring chamber 14 with graduation.

Pressure upon the pressure plate 114, preferably by the knee of the operator, who may work in a seated position, will move the piston 85 to the right until the channel 108 permits the liquid in the measuring chamber to flow downwardly into the ampoule injector 98. The proper centering of the channel 108 so as to permit an unobstructed passage therethrough is effected by the adjustment of the valve regulator 88. The filling of the ampoules generally indicated by numeral 150 thus becomes a very simple matter which may be performed with considerable rapidity. In actual tests with a model of the present device during an ordinary working day between six and seven thousand ampoules have been accurately

filled. The filling of each ampoule merely requires a pressure upon the plate 114.

While certain parts have been described as being made of metal or glass, in accordance with the present construction, all of the parts which will be contacted by the liquid being handled with the exception of the flexible couplers, may be composed of glass so that the complete disassembly of the machine and the sterilization of all of the parts which the liquid contacts is made a simple matter merely requiring the manipulation of the various clamping screws. The pin 120 and the link 86 are readily disconnected from the piston so that all of the parts in the valving mechanism 16 may also be sterilized. The flexible couplers may be composed of natural or artificial rubber tubing and they may either be sterilized or replaced as desired.

It may thus be seen that I have disclosed the construction of a novel and useful ampoule filling apparatus suitable for filling ampoules, vials, bottles and other containers which is extremely simple in construction, convenient and accurate both in use and in maintenance since individual parts, if broken, may be readily replaced and all of the parts may be separately sterilized.

I wish it to be understood that I do not desire to be limited to the exact details of construction shown and described for obvious modifications will occur to a person skilled in the art.

I claim:

1. A receptacle filling device comprising: a valve body having an elongated bore of uniform cross section throughout; a valve member of matching cross section closely fitting said bore throughout its length, and slidably longitudinally within said bore; a discharge outlet in communication with said valve body; a liquid measuring chamber in communication with said valve body; a reservoir located at a level higher than the level of said valve body in communication with said valve body; passageway means in said valve member for selectively connecting said reservoir to said measuring chamber, and said measuring chamber to said outlet upon rectilinear reciprocation of said valve body; and means manually operable to impart a movement solely of rectilinear reciprocation to said valve body.

2. A receptacle filling device comprising: a valve body having an elongated bore of uniform cross section throughout; a valve member of matching cross section closely fitting said bore throughout its length, and slidably longitudinally within said bore; an inlet port extending to and in communication with said bore; means placing said inlet port in communication with a reservoir located at a level higher than the level of said valve body; a first transverse passage in said valve member inclined with respect to the center line thereof; a second port in said valve body opposite said first-named port; a liquid measuring chamber in communication with said second-named port; a third port oppositely disposed in said valve body with respect to said second-named port and adjacent said first-named port; a second transverse passage inclined with respect to the center line of said valve member by an amount equal to the inclination of said first-named passageway but in the opposite direction; a discharge port spaced from said inlet port by an amount less than the spacing of the more widely spaced ends of said passageways; and means manually operable to impart a movement solely of reciprocation to said valve body.

JOHN TORIGIAN.
